REFRIGERATING APPARATUS

Jacob Smilack, Dayton, Ohio, assignor, by mesne assignments, to General Motors Corporation, a corporation of Delaware

Application December 30, 1931, Serial No. 583,925

3 Claims. (Cl. 62—4)

The present invention relates to refrigerating apparatus and the control thereof.

One of the objects of the present invention is to prevent the formation of such quantity of ice on a cooling unit of a refrigerating apparatus which would be detrimental to the efficient operation of the apparatus.

It is a further object of the present invention to provide mechanism which automatically will prevent an excess accumulation of ice on the cooling unit.

In carrying out the above objects, it is a still further object of the invention to modify temporarily and automatically the operation of the refrigerating apparatus when a predetermined amount of ice forms about the cooling unit and then automatically restore the apparatus for normal operation.

Further objects and advantages of the present invention will be apparent from the following description, reference being had to the accompanying drawing, wherein a preferred form of the present invention is clearly shown.

In the drawing:

Fig. 1 is a diagrammatic view of my improved refrigerating system; and

Fig. 2 is a front view of a refrigerator with the cabinet shown partly in section to illustrate the cooling unit and the location of a portion of the control mechanism with respect to the cooling unit.

For the purpose of illustrating my invention I have disclosed in the drawings, a cooling unit 20 herein shown as an evaporator similar in construction to that shown in the patent to Jesse G. King No. 1,654,504 of December 27, 1927, and includes a header 21 adapted to contain liquid refrigerant, which refrigerant is supplied thereto by a pipe 22 and is withdrawn therefrom through a pipe 23. The flow of refrigerant from the pipe 22 to the header 21 is controlled preferably by a float valve (not shown). A plurality of duct loops 24 are connected in parallel circuit relation to the header and are arranged to surround a freezing space 28 which may be employed, if desired, to receive ice trays or the like.

Any suitable means may be utilized for circulating a refrigerating medium through the cooling unit 20, the particular circulating means herein shown comprises a compressor 30 having its low pressure side connected to the pipe 23 for withdrawing refrigerant from the cooling unit 20 and having its high pressure side connected by a pipe 31 to a condenser 32. The compressed refrigerant is cooled in any suitable manner and

the liquid refrigerant is delivered to a receiver 33 which in turn is connected with the pipe 22 for supplying refrigerant to the cooling unit 20.

The compressor 30 is driven by a motor 35 through belt and pulley connections 36, 37, and 38. The circuit for the motor 35 includes wire 40, contacts 41 and 42, wire 43, contacts 44 and 45, wire 46 and wire 47. Normally contact 42 is in engagement with contact 41 to complete the circuit from wire 40 to wire 43. A controller 10 50 arranged to actuate contact 45 with respect to contact 44 normally functions to control operation of the motor 35 and compressor 30 to maintain the cooling unit 20 between certain temperature limits. Any suitable controller may 15 be utilized for this purpose, but I have herein shown for illustrating purposes a metal bellows 51 which is connected by a pipe 52 with a thermostat bulb 53. Bulb 53 may contain any suitable fluid capable of expanding and contracting in 20 response to temperature changes. This bulb 53 is disposed in the food storage compartment of the refrigerator cabinet and is adapted to control the refrigerating apparatus to maintain the food storage compartment between certain temperature limits. The fluid contained in bulb 53 25 upon contracting or expanding, due to temperature changes thereof will collapse or expand the bellows 51. Movement of bellows 51 actuates a lever 55 which operates a snap switch 56 including contacts 44 and 45. Therefore when the temperature in the food storage compartment increases to a predetermined high value the bellows 51 will be caused to expand to actuate snap switch 56 whereby contact 45 is caused to engage 35 contact 44 to thus complete the circuit to the motor 35 and start operation of the refrigerating apparatus. Conversely when the temperature within the food storage compartment is reduced, by the cooling effect produced by the evaporator 40 20, to a predetermined low temperature the bellows 51 will actuate contact 45 to open the electrical circuit to the motor 35. In this manner it is evident that the food storage compartment of the refrigerator cabinet will be maintained 45 between certain temperature limits.

Through continued use of the refrigerating apparatus ice collects upon the cooling unit due to condensation of water thereon and the freezing of such water, and, if a relatively large amount of 50 this ice is formed upon the cooling unit the efficiency of the apparatus is impaired because of the insulating qualities of the ice. Therefore it is desirable to prevent a large formation of ice upon the unit. It is customary to inform the 55

owner of a refrigerating apparatus to provide a manually operated switch for periodically interrupting the circuit to the motor whereby the refrigerating cycles are temporarily interrupted and the cooling unit becomes warm and the ice will melt. It has been found, however, that the owner of such refrigerating system will not give the proper attention to this defrosting method and permits ice to form on the unit, or, if he does 10 break the circuit, he fails to actuate the switch to again render the refrigerating apparatus operative and the error is not discovered until the products to be refrigerated become relatively warm and often are spoiled. In the present invention I have provided means which will automatically provide for the defrosting of the cooling unit. This defrosting means includes the contacts 41 and 42 which are actuated by a controller 65 which includes a metal bellows 66 and 15 a snap switch 67. The bellows 66 is connected with a thermo bulb 70 by a pipe 71. This bulb contains a quantity of water indicated at 72 and a quantity of oil 73. Preferably a quantity of oil may also be contained within the pipe 71 and bellows 66. By actual experiments I have found that 20 a charge of approximately two-thirds water and one-third oil in the bulb 70 is satisfactory.

In Fig. 2 the cooling unit 20 is shown within the cooling compartment 75 of a refrigerator cabinet 30 76. This cabinet is also provided with a storage compartment 77 which is separated from the cooling compartment 75 by a partition wall 78. Relatively warm air from the storage compartment 77 passes into the cooling compartment 75 through 35 a flue 79 and relatively cold air from the cooling compartment 75 flows through a flue 80 into the compartment 77. The thermo bulb 70 is shown in contact with the loops 24 of the cooling unit 20 and in the path of the relatively warm air entering 40 through flue 79 from the compartment 77. By locating the bulb 70 as herein shown the cooling unit may normally be operated at a temperature considerably lower than water freezing temperature without freezing a great quantity of the 45 water within the bulb because this bulb is also under the influence of relatively warm air entering from the compartment 77, which air is above water freezing temperature. Since the water and oil is confined within the bulb 70, pipe 71 and bellows 66, a temperature considerably lower than 50 water freezing temperature is necessary in the bulb 70 before the water therein is frozen solidly, because of the increase in pressure due to freezing, in such bulb, pipe and bellows.

55 In view of the foregoing and as long as the thermostat bulb 53, which causes operation of controller 58, tends to maintain the cooling unit between certain temperature limits, in accordance with an increase or decrease in temperature of the 60 food storage compartment 77 of the cabinet 76, the operating cycles of the refrigerating apparatus will be normal. However, during such normal operation of the apparatus, for maintaining the cooling unit 20 and consequently the food storage compartment 77 between predetermined normal temperature limits, moisture will condense and freeze upon the cooling unit. This accumulation of frost or ice on the cooling unit will increase after a certain period of time or continuous 65 use of the apparatus. It has been found that such an accumulation of frost or ice on the cooling unit insulates the unit, from the medium to be cooled thereby, and consequently the cooling unit must be reduced to a lower than normal temperature 70 in order to reduce the medium cooled there-

by to the desired low temperature. When this condition occurs it is obvious that the thermostat bulb 53, in the system disclosed, will cause longer than normal operating cycles of the apparatus. Obviously the operating cycles of the apparatus 5 will increase in time indefinitely and may continuously increase unless some provision is provided for defrosting the cooling unit. The longer than normal operating cycles causes the pressure within the cooling unit and likewise the temperature 10 thereof to be reduced to a point below normal. This abnormal decrease in temperature of the cooling unit causes all or at least a greater portion of the quantity of water in the thermostat bulb 70 to freeze and consequently the expansion 15 of the water during freezing in this bulb creates a pressure and tends to compress the oil in the pipe 71 and bellows 66. Compression of the oil thereby causes the bellows 66 to expand and actuate switch 67 to separate the movable contact 20 42 from the stationary contact 41, as shown by the dotted lines in Fig. 1 of the drawing, thus breaking the electrical circuit to the motor 35 of the refrigerating apparatus. The apparatus is thereby rendered inoperative to permit the relatively warm circulating air in the cabinet to increase the temperature of the ice on the cooling unit or to permit the ice on the cooling unit to be rapidly heated if desired by any suitable auxiliary artificial heating means or medium other 30 than the air in the cabinet to cause the ice or frost on the cooling unit 20 to melt. It is to be understood that, since the thermostat bulb 70 is in intimate thermal contact with the metal of the cooling unit 20, the ice within bulb 70 will not be 35 melted as quickly as the ice on the cooling unit and therefore the cooling unit will be defrosted, that is, substantially all of the ice accumulated thereon will be removed. As the ice melts from the cooling unit, and the temperature within and 40 of the walls of the cooling unit increases, to a predetermined degree ice within the thermal bulb 70 will then also become melted. However, due to the contact of bulb 70 with the cooling unit 20 and also due to the fact that the cutting in or 45 circuit making adjustment of switch 65 is set above 32° F., at which temperature ice freezes, it is to be understood that substantially all of the ice on the cooling unit will be removed before the ice in bulb 70 begins to thaw or melt. Melting of the ice in bulb 70 causes the pressure in bellows 66 to again decrease and this bulb then actuates the switch 67 to move contact 42 into engagement with contact 41 to thereby again complete the circuit to the motor 35 through the controller 58. Thus the system is again rendered operative automatically and cyclically operates in response to the controller 58, actuated by thermostat 53, and continues such operation until the accumulation of frost or ice on the cooling unit 60 again increases beyond the desired limit.

It will be apparent from the foregoing that by virtue of the present invention an excess quantity of ice, which is detrimental to the efficient operation of the refrigerating apparatus as hereinbefore pointed out, will be prevented from forming upon the cooling unit. It will also be apparent from the foregoing that the control for preventing the formation of ice on the cooling unit as herein described is entirely automatic and depends for its operation upon the accumulation of a predetermined abnormal amount of ice on the cooling unit and upon abnormal operating conditions of the system such as occurs as stated 70 75

when a predetermined amount of ice forms on the cooling unit of the system.

While the form of embodiment of the invention as herein disclosed, constitutes a preferred form, it is to be understood that other forms might be adopted, all coming within the scope of the claims which follow.

What is claimed is as follows:

1. A refrigerating apparatus comprising in combination, a cabinet, a cooling unit within said cabinet, means for circulating a refrigerant medium through said unit, a control responsive to the temperature of air in said cabinet for starting and stopping the refrigerant circulating means 10 to maintain said cooling unit between predetermined temperature limits, automatically operated auxiliary means for temporarily modifying the operation of the refrigerant circulating means to permit an increase above normal in the temperature of said unit, said auxiliary means including a stationary member having a portion thereof in intimate thermal contact with said cooling unit and disposed in the path of warm air circulating into contact with the unit whereby the warm air 15 affects said member to normally maintain the auxiliary means ineffective, and said member being responsive to a predetermined abnormal low temperature of the cooling unit for rendering said auxiliary means effective to prevent starting of the circulating means until a higher than normal temperature is reached in the cooling unit.

2. A refrigerating apparatus comprising in combination, a cabinet, an evaporator of a refrigerating system within said cabinet, means for circulating liquid refrigerant to and for withdrawing gaseous refrigerant from said evaporator, a control device responsive to the temperature of air in said cabinet for starting and stopping the refrigerant circulating means to maintain said evaporator between predetermined temperature limits, automatically operated auxiliary means for temporarily rendering said re-

frigerant circulating means inoperative to permit an increase above normal in the temperature of said evaporator, said auxiliary means including a stationary member having a portion thereof in intimate thermal contact with said evaporator and disposed in the path of warm air circulating into contact with the evaporator whereby the warm air affects said member to normally maintain the auxiliary means ineffective, and said member being responsive to a predetermined abnormal low temperature of the evaporator for rendering said auxiliary means effective to prevent starting of the circulating means until a higher than normal temperature is reached in the evaporator.

3. A refrigerating apparatus comprising in combination, a cabinet, an evaporator of a refrigerating system within said cabinet, means for circulating liquid refrigerant to and for withdrawing gaseous refrigerant from said evaporator, an electrical circuit for said refrigerant circulating means, a control device in said circuit responsive to the temperature of air in said cabinet for starting and stopping the refrigerant circulating means to maintain said evaporator between predetermined temperature limits, a switch interposed in said electrical circuit, a thermostat bulb having a portion thereof in intimate thermal contact with said evaporator and disposed in the path of warm air circulating into contact with said evaporator, said bulb having a connection with said switch for causing operation thereof but being normally maintained ineffective by the warm air circulating into contact with said evaporator, and said bulb being rendered effective by a predetermined abnormal low temperature of said evaporator to cause operation of said switch and temporary interruption in the operation of the refrigerant circulating means to permit an increase in temperature of said evaporator above a predetermined temperature limit thereof.
